(57) **CLAIM**

The ornamental design for an image for a portion of a display screen, as shown and described.

DESCRIPTION

FIG. 1 is a front view of an image for a portion of a display screen showing a first embodiment of our new design.

FIG. 2 is a front view of an image for a portion of a display screen showing a second embodiment of our new design; and,

FIG. 3 is a front view of an image for a portion of a display screen showing a third embodiment of our new design.

The broken line regions in the claimed design in FIG. 2 and FIG. 3 form no part of the claimed design. The broken line showing the display screen is for illustrative purposes only and forms no part of the claimed design.

FIG. 1

FIG. 2

FIG. 3

UNITED STATES PATENT AND TRADEMARK OFFICE
CERTIFICATE OF CORRECTION

PATENT NO. : Des. 529,919 S
APPLICATION NO. : 29/228371
DATED : October 10, 2006
INVENTOR(S) : Winjum et al.

Page 1 of 5

It is certified that error appears in the above-identified patent and that said Letters Patent is hereby corrected as shown below:

Delete Title page illustrating figure, and substitute therefor, new Title page illustrating figure. (attached)

Delete drawing figures 1-3, and substitute therefor drawing figures 1-3, as shown on the attached sheets.

Signed and Sealed this

Twenty-third Day of January, 2007

A handwritten signature in black ink, appearing to read "Jon W. Dudas", is centered within a dotted rectangular border.

JON W. DUDAS
